(57) **CLAIM**

The ornamental design for a high reach duster, as shown and described.

DESCRIPTION

FIG. 1 is an exploded front, right side perspective view of a high reach duster showing our new design;

FIG. 2 is a front view thereof;

FIG. 3 is a rear view thereof;

FIG. 4 is a left side view,

FIG. 5 is a right side view,

FIG. 6 is a top view thereof; and,

FIG. 7 is a bottom view thereof.

The material in dotted lines forms no part of our design.
